United States Patent Office

Des. 188,835
Patented Sept. 20, 1960

188,835

GLOVE

Stanley M. Hoffstein, Wilmington, Del., assignor to International Latex Corporation, Dover, Del., a corporation of Delaware

Filed Dec. 29, 1959, Ser. No. 58,845

Term of patent 14 years

(Cl. D3—11)

FIG. 1.

FIG. 2.

FIG. 3.

FIG. 4.

FIG. 5.

I claim:

The ornamental design for a glove, substantially as shown.
